UNITED STATES PATENT OFFICE.

CHARLES A. LOWE, OF DENVER, COLORADO.

COMBINED CAN OPENER AND SANITARY SEALER.

1,374,019.

Specification of Letters Patent.

Patented Apr. 5, 1921.

Application filed March 26, 1920. Serial No. 369,023.

To all whom it may concern:

Be it known that I, CHARLES A. LOWE, a citizen of the United States, residing at the city and county of Denver and State of Colorado, have invented certain new and useful Improvements in Combined Can Openers and Sanitary Sealers, of which the following is a specification.

My invention relates to a combined can 10 opener and sanitary sealer.

The object is to provide a simple device for attachment to cans of perishable liquid, such, for instance, as condensed or evaporated milk which will puncture the top when 15 desired and also serve to seal the opening air-tight, when desired.

A further object is to provide a device which can be easily cleaned and sterilized by removing it from the can and dropping 20 it in hot water or other sterilizing liquid.

With these objects in view, my invention consists in a band constructed and adapted to be clamped tight around a can adjacent to the flange of either end, and a lever 25 hinged thereto and provided with spurs which puncture the end of the can at two points, namely to form an outlet for the liquid and a vent for the inlet of air, and means for sealing these holes air-tight after 30 the can has been only partially emptied.

It consists also in other features of construction that will be hereinafter mentioned.

In the accompanying drawings:

Figure 1 is a top plan view;
35 Fig. 2 is a side view partly in vertical section;

Fig. 3 is a cross-section of the rim.

A, is a band, preferably of sheet-metal, which is fitted to, and adapted to embrace, 40 the can 1 close to the flange 2 of the head 3 of the can. This band may be secured in place in any approved manner, as for instance by the screw 4 and thumb-nut 5, which affords a simple mode of fastening.

An arm 6 is hinged at one end by the pin 45 7 to the upstanding hinge 8 forming an extension of the upper edge of the band, and projecting over the edge of the head of the can, and this hinge 8 with the two hooks 9, 50 tends to coöperate with the fastening device 4-5 to support the band in position contiguous to the flange 2 of the head of the can. The arm 6 reaches diametrically across the head of the can from the hinge as a fulcrum, and is preferably bent inwardly somewhat through the center to conform to the

shape of the head of the can, and is provided with the side flanges 10, which gives strength and rigidity to the arm.

The arm carries two sharp pointed conical spurs 11 and 12 in position to penetrate 60 the can head and form the two holes 13 and 14, the hole 13 for pouring out the liquid, and 14 to serve as an air-vent. These spurs are surrounded by a soft packing 15 of rubber or other compressible material adapted 65 to be held tight around the holes when the can is to be closed air-tight, and the arm is in its normal position, as shown in the drawings.

To hold the arm in this position, it is provided with a spring tongue 16, which springs over the inner edge of the flange 2 of the head, as shown clearly in Fig. 2, in this way holding the arm firmly in place and sealing 75 the can air-tight, in order to exclude extraneous material and prevent the contents from spilling or souring.

The tongue 16 may be conveniently struck out from the material forming the slot 17 in 80 the end of the arm.

To afford clearance for the tongue 16, the band A is slightly cut away as at 18.

The arm thus formed and fulcrumed immediately opposite the edge of the head of 85 the can has a powerful leverage, and the flange of the can head constitutes a shoulder which prevents the band from moving endwise when the pressure on the lever in penetrating the head might otherwise tend to 90 dislocate it, or pull it off, so that there is coöperation between the band, flange and arm both in the puncturing of the head and in sealing the holes when formed.

Thus I have provided a device which is 95 easily and quickly applied to a can of liquid for instance condensed milk, which is particularly useful where the entire contents of the can is not to be used at one time, as it not only forms an effectual can-opener for 100 any kind of liquid, providing both a liquid outlet and an air inlet, but also a means for effectively sealing the opening thus formed when the contents is not being poured, so that without regard to any position in which 105 the can may be placed the contents cannot leak or spill and the contents of the can is thus effectively preserved in its original condition, without permitting of deterioration or change in consistency or quality, and the 110 openings are also kept in a sanitary condition.

I claim:

1. The combination with a can having the usual flanged top secured thereon, of a band clamped around the can adjacent to the 5 flange of the top, so that the flange prevents the band from being pulled off the can, and an arm fulcrumed at one end upon the band and extending diagonally across the can head, and carrying means for puncturing 10 the can head, and means for fastening the free end of the arm when the latter is in its normal position.

2. The combination with a can of a band surrounding and embracing the latter, and

means for holding the band just inside the 15 flange of the can head, said means including a hinge and hooks opposite the latter, an arm connected at one end to the hinge, said arm curved inwardly and flanged at its edges 20 to give it rigidity, and carrying spurs adapted to puncture the end of the can, said spurs surrounded with compressible material to seal the openings formed by the spurs when the arm is in its fastened position, and means for fastening said arm.

In testimony whereof I affix my signature.

CHARLES A. LOWE.
